UNITED STATES PATENT OFFICE.

JOHN D. DAVALA AND WARD W. STALEY, OF FRANKFORT, NEW YORK; SAID DAVALA
ASSIGNOR TO SAID STALEY.

CLOTHESPIN HOLDER.

Application filed February 25, 1922. Serial No. 532,827.

To all whom it may concern:

Be it known that we, JOHN D. DAVALA and WARD W. STALEY, citizens of the United States, residing at Frankfort, in the county 5 of Herkimer and State of New York, have invented new and useful Improvements in Clothespin Holders, of which the following is a specification.

Our present invention has reference to a 10 means whereby clothes pins may be slidably suspended from a clothes line but effectively sustained thereon against accidental displacement.

An object is to provide a means whereby 15 any desired number of clothes pins can be slidably supported on a clothes line so that the removal of the pins from the line in detaching the clothes therefrom will be obviated and also whereby the pins will be conveniently sustained for use by the laundress 20 in hanging the clothes.

A further object is to produce a device of this character which shall be of an extremely simple construction, cheaply manufactured, 25 easily applied, of a nature not susceptible to deterioration from weather conditions and which will be found both convenient and desirable for the purpose intended.

A still further object is to produce a 30 clothes pin holder that includes a clamp of an especial design which is readily arranged over the head to engage the neck of a clothes pin, spring means connecting the clamp of an eye which is also of a peculiar and particular construction inasmuch as the same 35 comprises a split member whose ends are disposed in lapping relation and which ends, when pressed away from each other permit of the eye being arranged on the clothes line 40 or removed therefrom as desired.

The drawing which accompanies and which forms part of this specification, illustrates a satisfactory embodiment of the improvement reduced to practice, and 45 wherein:—

Figure 1 is a view of a clothes line showing clothes pins suspended therefrom in accordance with this invention.

Figure 2 is a greatly enlarged perspective 50 view of one of the clothes pin hangers showing the same attached to a clothes pin.

Figure 3 is a view of the catch that constitutes one of the elements of the improvement.

Figure 4 is a view of the eye which constitutes another element of the improvement. 55

Preferably all of the elements constituting our improvement are formed of metal, but are so treated as to render the same non-susceptible to rust or deterioration from exposure to weather conditions. 60

In the drawings, the numeral 1 designates a clothes line sustained at a desired elevation in the usual manner.

The clothes pins 2 are of the usual construction, being provided at their closed end with an enlargement forming the same with a head and with a reduced portion forming a neck at the juncture of the body of the pin with the head. 65

In carrying out our invention, we employ a clamp which is constructed from a strip of suitable spring metal shaped to provide the same with a split collar portion 3, the ends of which being outturned, as at 4, and the arms of the collar are designed 70 to be arranged around the neck of the clothes pin. The collar is centrally formed with an extension 5 bent to provide the same with a clamping finger 6 disposed centrally and longitudinally of the collar, the said finger 75 designed to overlie the head of the clothes pin and having its end bent toward the collar to form the same with a lip 7 that is in contacting engagement with one of the sides of the clothes pin head. Connected centrally 80 to the collar 3 there is a coiled spring 8, and the outer end of the said coiled spring is secured to the eye member 9 of our improvement. 85

The eye is also formed of a single flat 90 strip of spring metal bent upon itself to provide the same with a flat portion 11, the ends of the same being rounded in opposite directions to form the ring-like body of the eye.

The shorter element of the split ring-like body 95 is for distinction, indicated by the numeral 12, and the longer by the numeral 13. The ends of the portions 12 and 13 are disposed in lapping relation, the end of the portion 13 being outturned, as at 14 to provide a lip 100 which serves as a guide for the clothes line 1 when the shorter element 11 of the body of the eye is brought into contact with the said line, the said lip thereafter guiding the line between the split portions of the eye so that 105 the eye may be arranged thereon for suspending the pin therefrom.

Of course, any desired number of pins are

suspended from the line in a manner as above described. Because of its elasticity, the connecting element 8 between the eye and the clamp permits of the bifurcated end of 5 the pin being readily brought to engage with clothes that are disposed on the line and likewise readily permits of the removal of the pins from clothes engagement. The pins when not in use may be moved longitudinally 10 on the line in close relation to each other and may be conveniently drawn along the line by the laundress when the clothes are to be clamped on the line.

It is thought that the foregoing description, when taken in connection with the drawings will fully set forth the construction, operation and advantages of the improvement to those skilled in the art to which such inventions relate and therefore 20 further detailed description will not be attempted.

Having described the invention, we claim—

1. The combination, in a means for suspending clothes pins from a clothes line, of 25 a clamp arranged to engage the neck and head of a clothes pin, a resilient element connected to the clamp, and a split spring eye

designed to be arranged on the clothes line connected to the said element. 30

2. The combination, in a means for suspending clothes pins from a clothes line, of a spring clamp formed to provide a split collar arranged around the neck of a clothes pin having an extension terminating in a finger 35 which overlies the head of the clothes pin and the said finger having its outer end formed with a lip which is in contacting engagement with one of the sides of the clothes pin, a resilient element connected to the 40 clamp, and a split spring eye secured to the element and arranged on the clothes line.

3. The combination, in a means for suspending clothes pins from a clothes line, of a spring clamp to engage with the head and 45 neck of a clothes pin, a coiled spring secured to the clamp, a split spring eye secured to the spring, said eye having its ends at the split portions thereof disposed in lapping relation and the end of the outer portion 50 bent to provide a lip to facilitate the arrangement of the eye on the clothes line.

In testimony whereof we affix our signatures.

JOHN D. DAVALA.
WARD STALEY.
